FEEDING DOLL WITH BITING ACTION

Carl A. Philippi, New York, N. Y.

Application March 10, 1949, Serial No. 80,647

8 Claims. (Cl. 46—141)

1

This invention relates to dolls and describes a construction whereby a doll can bite off and appear to eat thin, brittle, wafer like food so as to reproduce with great fidelity the human process of eating.

A further object of the invention is to provide means within the body of the doll for collecting the particles of food that have been bitten off and to provide means for their periodical removal from within the doll's body.

A still further object of the invention is to provide means for conveying food in the form of thin soda crackers or other thin brittle food-stuffs to the doll's mouth, the doll's own hand holding the food.

The objectives of my invention are illustrated in Fig. 1 to Fig. 9, and the biting mechanism is shown in three variations of the same general concept.

Fig. 1 is a cross-section side view through the head and body of the doll and with Figs. 2 and 3, show the first variation of the biting mechanism.

Fig. 2 is a cross-section back view through the head and body of the doll and, together with Fig. 1 illustrates the food collecting and disposing means within the doll's body.

Fig. 3 shows a detail of the bent lever mechanism used in Figs. 1 and 2 for producing the biting action of the teeth.

Fig. 4 shows details of arm movement for conveying wafer from side of doll to mouth.

Fig. 5 shows details of arm socket and of hand formed to hold wafer.

Fig. 6 is another cross-section side view through the dolls' head and body and illustrates the second variation in construction embodying the biting phase of the invention.

Fig. 7 shows a detail of the biting lever used in Fig. 6.

Fig. 8 is again a side cross-section of the doll's head and body and shows the third variation in construction of the biting feature of the invention.

Fig. 9 is a detail of the lever used for biting in Fig. 8.

Referring now to Fig. 1. I show a doll's head and body, the head having a mouth aperture 10. The upper teeth 11 being fastened rigidly to the doll's head. The active biting unit is the bent lever shown in Fig. 3 and pivoted at 12, Fig. 1, with the lower teeth 13 normally positioned just below the mouth opening, by the action of the spring 14, and the long arm 15 of the biting lever resting against the inside of the doll's back at 16. At this point there is an aperture 17 in the doll's

2

body through which a knob 18 protrudes from the long arm of the lever 15. By pushing the knob 18, the lower teeth are caused to move upward in a biting action.

Fig. 2 shows how this biting unit 15 is pivoted and centered on the rod 12 which is inserted in the doll's head at 19, right and left.

The container 20 in which the food is collected is shown in Figs. 1 and 2 and extends the entire width of the body. It rests on a base plate 21, Figs. 1 and 2, which is fastened solidly to the walls of the body. The container can be slid out of the doll by pulling on that portion of the side wall 22, Fig. 2, using the finger hole 23 provided.

Figs. 1 and 2 show guide plates 24 for guiding the food into the container 20 and one of these plates has an opening 25, Fig. 1, to allow the long lever arm 15 to pass through.

20 An alternate construction of the food container makes it non-removable and fastened rigidly within the doll's body. In this construction there are no side walls 20a and 20b and the container is emptied simply by removing the cover 22 and 25 tilting the doll's body in the direction of the opening.

Fig. 3 shows the biting lever in detail with teeth 13 which are formed from the metal of the lever itself and bent upward as shown. The tongue 28 is also formed from the metal of the biting lever and serves a double purpose, first as a stop for the wafer and also to conceal the inner mechanism as viewed through the mouth cavity.

35 Fig. 4 shows in solid line the left arm and hand holding the wafer at the side of the body. Also in dotted line, the final position of the arm and hand registering perfectly to allow the wafer to enter the mouth of the doll when the arm is 40 pushed forward and upward. The right arm and hand are made to operate in a similar manner except that a napkin is held in the doll's hand as shown.

Fig. 5 shows the inward angling of the arm 45 socket to cause proper registry of hand to mouth in the self-feeding phase of this invention. Also shown in Fig. 5 are the fingers of the doll's hand so positioned as to receive a specially formed narrow elongated wafer, 27 and to hold it in a 50 fixed and relatively immovable position.

Fig. 6 is a side cross-section through the doll's head and body and shows the second modification of the biting mechanism. A short straight lever 29 is pivoted at 12 and a cord or chain 30 attached to the end of the lever at 31 runs down through

the hold in the guide plate 25 and then outward through the aperture in the doll's back 17. A ring 32 is fastened to the end of the cord or chain. By grasping the ring and pulling, an upward biting action of the lower teeth is produced and the teeth 13 will always return to the position shown and will rest on the stop 33 due to the action of the spring 14. Fig. 7 shows the detail of the short biting lever used in Fig. 6.

Fig. 8 illustrates the third modification in construction of the biting mechanism shown in side cross-section of the doll's head and body. Here too a short straight lever is used, but the pivot is at the extreme end 34 opposite to the end carrying the teeth 13. Between the teeth 13 and the pivot 34 a rod 35 is loosely fastened at 36. This rod extends downward through the opening in the guide plate 25 and then outward through the orifice 17 in the doll's back. At the end of the rod a ball or knob 37 is attached. By forcing the ball upward, this motion is transmitted to the lever 33 and the lower teeth move upward in a biting action. They will fall again to the original position and rest on the stop 33 due to the weight of the mechanism and so no spring is required in this construction. Fig. 9 shows detail of the short lever with pivot-rod 34, the loose connection 36, and the rod 35. Teeth and tongue construction is similar to Fig. 3 and Fig. 7.

In all the foregoing descriptions I have confined myself to that form of mechanism in which the upper teeth are stationary while the lower teeth are caused to move. This method has been chosen as providing the simplest mechanism and being closest to the human biting and eating action. It would, however, require only slight changes in the mechanism to cause the upper teeth to move or both upper and lower teeth to move in a biting action.

What I claim is:

1. A doll comprising a head having a mouth aperture formed therein, means simulating rows of upper and lower teeth located within said head adjacent to said aperture and at least partly visible therethrough, means connected with the first-mentioned means for normally positioning said rows of teeth slightly apart, and externally accessible and manually operable means for bringing said rows of teeth together with pressure, whereby said teeth are adapted to bite off a brittle article inserted into said mouth aperture.

2. A doll comprising a head having a mouth aperture formed therein, means located within said head and attached thereto adjacent to said aperture for simulating a row of upper teeth, said upper teeth being at least partly visible through said aperture, means located within said head adjacent said upper teeth for simulating a row of lower teeth, means connected with the second-mentioned means for normally positioning the lower teeth slightly apart from the upper teeth, and externally accessible and manually operable means connected with the last-mentioned means for forcing the lower teeth with pressure against the upper teeth, whereby said teeth are adapted to bite off a brittle article inserted into said mouth aperture.

3. A doll comprising a head having a mouth aperture formed therein, a member located within said head adjacent to said aperture and simulating a row of upper teeth, another member located within said head adjacent to said aperture and simulating a row of lower teeth, at least some of said teeth being visible through said

aperture, means firmly connecting one of said members to an inner wall of the head, means movably supporting the other one of said members, means connected with the second-mentioned means for normally positioning said rows of teeth slightly apart, and externally accessible and manually operable means connected with the second-mentioned means for bringing said rows of teeth together with pressure, whereby said teeth are adapted to bite off a brittle article inserted into said mouth aperture.

4. A doll comprising a head having a mouth aperture formed therein, means located within said head and attached thereto adjacent to said aperture for simulating a row of upper teeth, said upper teeth being at least partly visible through said aperture, means located within said head adjacent said upper teeth for simulating a row of lower teeth, a lever carrying the last-mentioned means, means pivotally supporting said lever within said head, means connected with said lever for normally positioning the lower teeth slightly apart from the upper teeth, and externally accessible and manually operable means connected with said lever for forcing the lower teeth with pressure against the upper teeth, whereby said teeth are adapted to bite off a brittle article inserted into said mouth aperture.

5. A doll comprising a body and a head having a mouth aperture formed therein, means simulating rows of upper and lower teeth located within said head adjacent to said aperture and at least partly visible therethrough, means connected with the first-mentioned means for normally positioning said rows of teeth slightly apart, externally accessible and manually operable means for bringing said rows of teeth together with pressure, whereby said teeth are adapted to bite off a brittle article inserted into said mouth aperture, a container, means supporting said container within the body and guiding bitten-off particles to said container, said body having an opening formed therein and positioned to empty contents of said container without removing the container when the doll is tilted toward the opening, and a closure for said opening.

6. A doll comprising a body and a head having a mouth aperture formed therein, a member located within said head adjacent to said aperture and simulating a row of upper teeth, another member located within said head adjacent to said aperture and simulating a row of lower teeth, at least some of said teeth being visible through said aperture, means firmly connecting one of said members to an inner wall of the head, a bent L-shaped lever having one arm supporting the other one of said members, and means pivoting said lever near the angle of the "L" thereof within said doll, the other arm of said lever extending into the body and being adapted to rest near a wall of the body, said body wall having an opening formed therein of a size permitting manual movement of said lever from outside.

7. A doll comprising a body and a head having a mouth aperture formed therein, a member located within said head adjacent to said aperture and simulating a row of upper teeth, another member located within said head adjacent to said aperture and simulating a row of lower teeth, at least some of said teeth being visible through said aperture, means firmly connecting one of said members to an inner wall of the head, a lever pivoted intermediate its ends within said head and having an end supporting the

other one of said members, and a cord attached to the other end of said lever and having an end extending outwardly through an opening formed in the body of the doll.

8. A doll comprising a body and a head having a mouth aperture formed therein, a member located within said head adjacent to said aperture and simulating a row of upper teeth, another member located within said head adjacent to said aperture and simulating a row of lower teeth, at least some of said teeth being visible through said aperture, means firmly connecting one of said members to an inner wall of the head, a lever pivoted within said head and having an end supporting the other one of said members, and a rod having one end pivoted to said

lever and having another end extending outwardly through an opening formed in the body of the doll.
